Filed Nov. 19, 1963, Ser. No. 77,489

Term of patent 14 years

(Cl. D52—2)

FIG. 1

The undisclosed side of the container is substantially the same as the side shown and the undisclosed rear of the container is flat and plain in appearance. The bottom is flat and plain.

The dominant features of the design reside in the portions shown in full lines. The broken lines are intended to represent surface ornamentation simulating an automobile.

I claim:

The ornamental design for a children's tissue dispensing container, as shown and described.
